UNITED STATES PATENT OFFICE.

JAMES SHORTT, OF LOS ANGELES, CALIFORNIA, ASSIGNOR TO ALLOY METAL PRODUCTS CO., OF LOS ANGELES, CALIFORNIA, A COPARTNERSHIP COMPOSED OF JAMES SHORTT AND CLAUDE E. CHAPMAN.

DESIGN FOR A PANEL FOR ELECTRIC-LIGHT FIXTURES.

Application filed May 9, 1928. Serial No. 26,614. Term of patent 3½ years.

To all whom it may concern:

Be it known that I, JAMES SHORTT, a citizen of the United States, residing at Los Angeles, in the county of Los Angeles and State of California, have invented a new, original, and ornamental Design for a Panel for Electric-Light Fixtures, of which the following is a specification, reference being

had to the accompanying drawing, forming part thereof.

Fig. 1 is a front elevation of my design.

Fig. 2 is an end elevation of my design.

I claim:

The ornamental design for a panel for electric light fixtures, as shown.

JAMES SHORTT.
